By B. Amher, Atty

UNITED STATES PATENT OFFICE.

THOMAS GORDON JONES, OF NEWPORT, ENGLAND.

METAL SEAL.

1,356,152.

Specification of Letters Patent. Patented Oct. 19, 1920.

Application filed September 15, 1919. Serial No. 323,878.

To all whom it may concern:

Be it known that I, THOMAS GORDON JONES, a subject of the King of Great Britain and Ireland, residing at Newport, in the county of Monmouth, England, have invented new and useful Improvements in Metal Seals, of which the following is a specification.

This invention relates to metal seals of the strap type and is more particularly intended for the purpose of securing the doors and windows of railway cars, although it may be used with advantage for securing devices generally where it is desired to prevent them being opened or tampered with by an unauthorized person.

In the accompanying drawings, which illustrate the invention:

Figure 1 is a plan of a metal strap, stamped to the required shape to form the blank.

Fig. 2 is a plan of the same piece of metal with the flaps hereinafter referred to turned into position.

Fig. 3 is a section illustrating the bending of the tongues at the end B.

Fig. 4 is a perspective view showing the seal secured and also illustrating the covering member provided to protect the springs from interference.

The strap or device is stamped, or otherwise formed, as shown at Fig. 1.

At the end A it is provided with a stamped out hole a, into which a lug b projects, as clearly seen in the drawing.

At the opposite end B, the metal is stamped with two flaps c and d, and with two spring tongues s and t, the tongue t being stamped in the tongue s and pointing in the reverse direction thereto.

The flaps c and d are then folded or turned over along the lines e f and g h Fig. 1 until they come into the position shown at Fig. 2 at a suitable distance above the surface of the strap and the tongues s and t; the spring s being pushed upward until it is held by the shoulders p and q of the flaps. The small spring t is pushed well down and then its point is elevated until it is almost upon a level with the spring s.

The edge of the lug b is also elevated slightly.

A suitable covering is provided, indicated diagrammatically by dotted lines at Fig. 4.

This cover is fixed over the shoulders e f, 55 g h of the flaps, both above and below, and may be cylindrical or egg shaped.

To use the seal, the end A is inserted through the hole in the iron catch of a truck door and through the iron loop fixed 60 to the door way, in the case of securing a truck door. The end is then bent over and

inserted in the gap indicated beneath the projecting lug r and the point v. It passes over the upper surface of the spring s, forcing the latter down until the point of the lug b passes the point of the spring s, when 65

the latter springs upward resuming its original position. The end A is then withdrawn along the under surface of the spring 70

s, until the upper surface of the said spring s is caught by the shoulders p q, and held fast. As the lug b is drawn along the under surface of the small spring t, the latter 75

is forced slightly upward. On pushing the end A forward once more, the edge k l of the hole a (see Fig. 2) is caught by the under surface of the small spring t and held. The 80

end A is now secured, so that it can neither be pushed forward nor pulled backward. Moreover it cannot be maneuvered from side to side.

The action is of course the same when applying the device for securing a truck window or other device.

Metal band seals have already been proposed in which an end, protected by a covering, is formed of a locking spring upon which an aperture in a bent tongue formed at the opposite end of the band engages.

Devices of this description do not afford the security obtained with those constructed according to my invention.

It will be seen that the present device provides an additional means of engaging 95 the tongue, namely the second spring stamped out of the main spring in the reverse direction, which prevents the tongue, when once secured, from being moved longitudinally in a forward direction. In addition,

owing to the construction and arrangement of the flaps, one on either side of the inclosed end, the space in which the main spring, and hence the tongue, can be maneuvered longitudinally in a backward direction is restricted, and the tongue cannot be maneuvered laterally in an effort to disengage it.

What I claim and desire to secure by Letters Patent of the United States of America is:—

- 5 1. A metal seal of the strap type comprising an elongated metal strip provided at one end with a hole, a tongue projected partly across said hole and located centrally thereof, flaps formed on opposite sides at the opposite end of said strip and folded 10 over toward each other, a spring stamped out centrally between said flaps and having a width equal to the width of the hole in the opposite end of the strip, and a second spring stamped out in the first mentioned 15 spring and extending in a direction opposite thereto, for the purposes set forth.
2. A metal seal of the strap type comprising an elongated metal strip provided at one end with a hole, a tongue projecting 20 partly across said hole and located centrally thereof, said tongue being elevated from the strip toward its free end, flaps at the opposite sides at the opposite end of said strip and folded over toward one another so as 25 to leave a space between the strip and the flaps to receive the opposite end of the strip, a spring stamped up from the strip between the flaps and having its free end pointing toward the adjacent end of the 30 strip, a second spring stamped out of the first mentioned spring and having its free end directed oppositely thereto, the first

mentioned spring being elevated at its free end toward the flaps, while the other spring is pushed well down away from the flaps 35 and has its point elevated until it is almost level with the first mentioned spring, for the purposes described.

3. A metal seal of the strap type comprising an elongated metal strip, a hole 40 in one end of said strip, a lug projecting partly across the center of said hole and having its free end directed away from the adjacent end of the strip, a spring stamped up from the strip in the neighborhood of 45 its opposite end, and corresponding in width to the width of said hole, a second spring stamped up from said first mentioned spring and corresponding in width to the width of the lug at the opposite end of the strip, the 50 points of said springs being directed in opposite directions, a flap on one side of said strip adjacent said springs, a second flap on the opposite side of said springs, so that their outer edges face one another to produce a guideway through which the opposite end of said elongated strip is passed, said springs and the lug projecting across the recess the one of the strips being elevated from said strip to enable the same 55 to be interlocked for the purpose set forth.

Dated this 18th day of August 1919.

THOMAS GORDON JONES.
